JAMES H. MONTROSE, OF NEW YORK, N. Y.

Letters Patent No. 72,667, dated December 24, 1867.

IMPROVEMENT IN HINGED FISHING-ROD.

The Schedule referred to in these Letters Patent and making part of the same.

TO ALL WHOM IT MAY CONCERN:

Be it known that I, JAMES H. MONTROSE, of the city of New York, and county and State of New York, have invented a certain new and improved Fishing-Pole; and I do hereby declare that the following is a full and exact description thereof.

My pole is a jointed pole, and can be adjusted in one-half the time consumed with the ordinary pole, and also does away the liability or even the possibility of losing or dropping a section in the act of putting it together. The invention is also intended to obviate the difficulties heretofore experienced in consequence of the liability of the ordinary jointed fishing-pole to pull apart in the act of ordinary fishing, or more especially in case of an entanglement of the line, so as to require a strong end-pull on the sections. The joints are permanently connected together by a hinged joint, which is so made and defended as to be very strong, and to allow the parts to be folded into a very compact condition.

I will first describe what I consider the best means of carrying out my invention, and will afterwards designate the points which I believe to be new. The accompanying drawings form a part of this specification.

Figure 1 represents my entire pole in three lengths or sections, folded.

Figure 2 is a cross-section on the line S S in fig. 1.

Figure 3 is one view of a joint extended, but not stiffened.

Figure 4 is another view of the same.

Figure 5 shows the pole stiffened.

Similar letters of reference indicate like parts in all the figures.

Tints are employed to aid in distinguishing parts, and do not indicate materials. The material of the wood parts may be ash. The material of the metallic parts may be all brass, with or without silver plating or other ornamentation. The drawings represent the novel parts, with so much of the ordinary parts as is necessary to indicate their relation thereto. It will be understood that my invention may be provided with any of the approved reels and other devices known to the craft.

A is the woody portion of the butt or largest section. A¹ is a metallic ferrule, which defends the end against the liability of being split or otherwise injured. B is a short link or hinged piece jointed to the piece A at one end by the rivet or pin b¹, and to the second piece or section of the pole C by the rivet b². The second section C of the pole is protected at both ends by ferrules, as represented, and is jointed to the third section E by the link or hinge-piece D and the pins d¹ d². The ends of the several pieces A, C, and E, are rounded, as represented, and are adapted to fit close together, as also to allow the sections to be folded upon each other, as represented. It will be observed that the linked pieces B and D are allowed to lie parallel to each other, and that the plane of the hinge-piece D is held at such an angle that when the several sections are folded, the section C does not lie exactly at the side of either the piece B, the piece C, or the piece A, but rather in the joint, or opposite to the space between them. This allows the pole to be folded in a very compact form. When the number of sections is increased the same principle of construction may be carried further, so as to involve any number of sections, and the additional sections may be disposed relatively to the others, so as to form therewith the most compact shape, it being generally preferable to make a round bundle, or a bundle which is slightly flattened, or which is round on one side and flat on the other.

I believe it unnecessary to point out all of the positions of the joints which will be required to effect these several ends. I may suggest, however, that in order to make the bundle as nearly round as possible when the parts are folded together, it may be well to extend the small end of the section E a little beyond the sections A and C, so that its link or hinge-piece may extend directly across the ends of the previously-folded sections, this bringing the next and additional piece in the opposite joint or space on the other side of the sections A and C. This condition of the parts is indicated in fig. 1.

Having now fully described my invention, what I claim as new therein, and desire to secure by Letters Patent, is as follows.

I claim a sectional fishing-pole, having the several sections A, B, C, &c., permanently connected by hinged joints, constructed and arranged relatively to the sections and to each other, substantially as and so as to fold in the manner herein described.

In testimony whereof, I hereunto set my hand in the presence of two subscribing witnesses.
